DESIGN FOR A SAFETY RAZOR OR SIMILAR ARTICLE

John Evans, Union, N. J., assignor to Consolidated Razor Blade Co. Inc., Jersey City, N. J., a corporation of New Jersey

Application November 2, 1945, Serial No. 123,422

Term of patent 14 years

(Cl. D22—3)

To all whom it may concern:

Be it known that I, John Evans, a citizen of the United States of America and a resident of Union, Essex County, State of New Jersey, have invented a new, original, and ornamental Design for a Safety Razor or Similar Article, of which the following is a specification, reference being had to the accompanying drawing, forming a part thereof, in which

Figure 1 is a top plan view of a safety razor, or similar article, showing my new design; Fig. 2 is a side elevational view thereof; and Fig. 3 is an end elevational view thereof.

I claim:

The ornamental design for a safety razor or similar article, as shown.

JOHN EVANS.
